UNITED STATES PATENT OFFICE

JOHN EDWARD GLOEKLER, OF PITTSBURGH, PENNSYLVANIA

REFRIGERATOR SHOW CASE

Application filed March 21, 1928. Serial No. 263,284.

My invention is an improvement in the class of refrigerator show cases for displaying meat, fish, butter, vegetables or other perishable provisions. It has for its object to provide a show case of novel, attractive and efficient construction, embodying a self-draining refrigerating chamber so constructed as to be concealed from view within the upper portion of the case, with clear containing space below. Also to provide, in the construction of the refrigerator chamber, for ample and free downward circulation of cold air from its bottom into and through the containing or display space and upwardly therefrom of warmer air to the top of the refrigerator chamber.

A further object is to provide a construction embodying an upper separate illuminating compartment in front of the refrigerating chamber, together with other features of construction and advantage, as shall be more fully described.

Referring to the drawings:—

Fig. 1 is a perspective view of a show case embodying my invention;

Fig. 2 is a partial cross section thereof of the upper portion, enlarged;

Fig. 3 is a partial vertical section on the line III—III of Fig. 2.

The show case as a whole is generally rectangular in plan, having a backwardly sloping front for the containing and display space A, terminating in a narrower upwardly projecting portion B embodying the refrigerator chamber. In the construction shown the lower base portion C is utilized for storage and limited refrigeration, within the main enclosing walls 2 and ends 3, with rear doors 4 of any suitable kind opening to the interior, and front closing panels 25.

Extending across between the lower base portion C and its contained storage space c, and the middle section A and its contained display space a, is a transverse floor partition 5 framed into or supported by the front and back wall structure 2, and the ends. Such partition may be sufficiently open, if desired, for air circulation between the chambers for limited refrigeration of the lower chamber, or tight as preferred.

The rear wall of the cabinet extends upwardly at the back to the full extent of its height, as shown, terminating in a closed wall section 6 forming the rear closure for the refrigerator section B and its interior b. 55 Sliding or swinging doors 7 provide closing access to the chamber a from the rear and may, if preferred, be provided with glass panels 8.

The front of the section B is composed of an inner partition 9 extending downwardly from the covering top 10 and providing between it and rear wall 6 the ice containing or refrigerating chamber b opening downwardly into chamber a. The outer front of section B is closed by a light wall or glass pane 11 mounted in framing 12, 13, and providing between it and wall 9 the illuminating cavity 14.

This cavity is provided at its top with one or more lamps 15 adapted to shed rays of light outwardly through pane 11 and downwardly through a lower closing pane 16 to the interior a.

In this manner the light cavity 14 is closed off from the interior, avoiding any heat transmission from the lamps. The ends of the cabinet are closed by solid end walls 17 with separate panels 18 of glass, or otherwise may be used for exposure of the contents of chamber a, in harmony with any particular design of the cabinet which may be adopted.

For the purpose of supporting ice within the refrigerator chamber b I utilize inner partition walls 19 spaced inwardly from walls 6 and 9. Walls 19 terminate below the inner surface of top 10 providing ample circulating space for upwardly moving currents of warmer air passing from the main interior a to the top of chamber b, and are provided with inwardly extending sloping drip extensions 20 having downwardly turned lip edges 21.

Walls 19—20 are of any suitable material, and preferably embody one or more linings or layers of insulating material, as felt, paper, or the like, for prevention of heat transmission.

The ice is supported upon a series of spaced apart cross slats 22 of inverted channel or 100

other form, carried between and upon the walls 19 and their inward extensions 20, as in Fig. 2.

For the purpose of collecting drip water from the melting ice, a shallow drip pan 23 is mounted and extends between the end walls 17 for the full length of chamber *b*. As shown the pan is sufficiently wide to extend beyond the inner edges of sloping extensions 20 and is located below them sufficiently far to provide ample intervening circulating space for downwardly moving currents of cold air, as indicated.

A drain pipe 24 leads downwardly from the bottom of the pan at one or both ends to any suitable point of discharge, for carrying off water collected in the pan.

The top 10 is removable for renewal of ice, cleaning, etc., and the cabinet as a whole is well constructed and adapted to its purpose.

The refrigerating chamber is entirely above the main cavity *a* and completely concealed from view, while providing by its outer framing and top a feature of ornamental value and utility, for placement of any desired units.

The illuminating section 14 adds a feature of utility and finish to the complete cabinet, and greatly assists in the display of commodities in the interior *a*. As shown, the illuminating cavity occupies but a small portion of the cross section of the portion *B*, leaving the major portion available for the refrigerant, while the front and ends of the cabinet surrounding the interior *a* are of glass, as shown.

What I claim is:—

In a show case refrigerator, the combination with a supporting base having a floor, end walls, and a top, of a vertical back wall between the floor and top at one side, an upper outer transparent front wall at the opposite side extending from the top partially towards the floor, an inner front wall extending from the top co-extensive with said transparent wall and connected therewith by a lower transverse wall providing an enclosed illuminating chamber, an illuminant therein, a front transparent wall extending from the upper outer transparent wall to the floor and providing with the back wall a main commodity chamber, an ice supporting casing located immediately below the top and between the back wall and the inner front wall consisting of side walls spaced inwardly therefrom and downwardly from the top for circulation and having inwardly sloping extensions converging towards a middle open bottom, and a drip pan located below and extending at each side beyond said extensions for collection of water and providing intervening circulation.

In testimony whereof I hereunto affix my signature.

65 JOHN EDWARD GLOEKLER.
